UNITED STATES PATENT OFFICE.

JAMES CONNELL PARKER, OF WOODSTON, KANSAS.

SHEAF-TIE.

SPECIFICATION forming part of Letters Patent No. 748,783, dated January 5, 1904.

Application filed November 22, 1902. Serial No. 132,457. (No model.)

To all whom it may concern:

Be it known that I, JAMES CONNELL PARKER, a citizen of the United States, residing at Woodston, in the county of Rooks and State of Kansas, have invented a new and useful Sheaf-Tie, of which the following is a specification.

This invention relates to a novel tie or binder for binding a sheaf of corn or other cereal.

The object of the invention is to produce a tie adapted particularly for use in connection with a sheaf-forming device invented by me and disclosed in my concurrent application, No. 132,153, for Letters Patent, the tie being provided with series of catches disposed adjacent to its ends to facilitate the automatic connection of said ends when brought together at one side of the sheaf, around which the tie is placed.

To the accomplishment of this object the invention in its preferred embodiment resides in those features of construction and arrangement to be hereinafter described, illustrated in the accompanying drawings, and succinctly defined in the appended claim.

In said drawings, Figure 1 is a plan view of one form of tie. Fig. 2 is a perspective view showing the manner in which the catches interlock to connect the ends of the tie. Fig. 3 is a view similar to Fig. 1, showing another form of tie. Fig. 4 is a perspective view illustrating the manner in which the catches interlock. Fig. 5 is a sectional view showing two catches about to be drawn into engaging relation, and Fig. 6 is a perspective view showing another way in which the catches may be engaged.

Like characters of reference are employed to designate corresponding parts throughout the several views.

Referring first to Figs. 1 and 2, 1 indicates a tie, which is preferably a continuous strand of wire formed at its opposite ends with double-ended catches 2 and 3. Each of the catches is in the form of a loop 4, disposed lengthwise of the tie and connected thereto by a shank 5, formed by intertwisting a double strand of the wire. The doubling of the wire to form the shanks 5 materially increases the stability of the connection between the ends of the tie and renders them

sufficiently stiff to maintain the loops 4 in their proper positions in spaced relation to the tie, so as to facilitate their engagement when brought together. The catches 2 are disposed at the side of the tie opposite the catches 3, so that as the tie is brought around the sheaf oppositely-disposed catches at opposite ends of the tie may be readily brought into interlocking engagement, two shanks contacting with each other and the loops extending beyond the opposite sides of the tie proper, as shown in Fig. 2. By forming the tie with series of oppositely-disposed double-ended catches at its ends it may be drawn tightly around sheaves of different sizes and locked by bringing the ends of the tie in crossing relation; so as to present two catches in position to engage each other, and by then permitting the expansion of the sheaf to draw the two catches into the positions shown in Fig. 2.

While the form of tie thus far described is, perhaps, preferable by reason of its strength, simplicity, and inexpensiveness, a further embodiment of the invention (shown in the last four figures of the drawings) is precisely as effective and is equally well adapted for manipulation by the sheaf-former disclosed in my other application. This embodiment of the invention comprehends a tie 1^a, formed by intertwisting two strands, preferably formed by doubling a single length of wire upon itself. Adjacent to the ends of the tie 1^a the latter is provided with catch-blocks 2^a and 3^a, each of which is provided with a V-shaped notch 6 in each end thereof, defining a shank 7, passed between the strands of the tie and connecting a pair of double-ended catches 8 and 9, located at opposite sides of the strand and disposed lengthwise thereof. In this form of tie, as in the other, it is simply necessary to bring its ends together and to permit the expansion of the sheaf to draw two of the blocks into engaging relation, the tie adjacent to one block being passed into the notch 6 of an adjacent block, as shown in Fig. 5, and drawn back until the two blocks engage, as shown in Fig. 4, it being noted that by reason of the double-ended formation of the notches it is immaterial which way the band is bent around the sheaf or what positions the blocks may assume, provided only

that they may be engaged by the crossing and drawing back of the ends of the tie. To facilitate the retention of the tie within the notch 6, each block is formed at the base or 5 inner end of each notch with a substantially circular recess 10. When two of the blocks are brought into engaging relation, the tie will enter the notched end of the block, as stated, and will be received within a recess 10, from which it will not become readily disengaged. It is not absolutely essential that this character of connection between the blocks be effected in order to secure the ends of the tie, because if it should happen that 15 two adjacent blocks should be disposed at right angles to each other the shank of each will be received within a notch of the other and an engagement, such as is shown in Fig. 6, will thus be effected.

20 It will be observed from the foregoing that I have produced a novel tie designed to constitute a binder for a sheaf and provided with oppositely-disposed double-ended catches at its opposite ends arranged to automatically engage when the tie is passed around a sheaf and its ends crossed either by manual manipulation or by means of a sheaf-forming device.

25 It is thought that from the foregoing the construction and mode of manipulation of the tie will be clearly apparent; but while the illustrated embodiments of the invention are

believed at this time to be preferable I do not limit myself to the structural details defined, but, on the contrary, reserve to myself the 35 right to effect such changes, modifications, and variations of the illustrated structure as may be fairly embraced within the scope of the protection prayed.

What I claim is—

40 A sheaf-tie, provided at each end with a series of double-ended catches disposed lengthwise of the strand, and connected to said strand by transversely-disposed shanks, the catches of one series being located at the side 45 of the strand opposite the other series of catches, the intervals between the catches of each series corresponding to the intervals between the catches of the other series, whereby when the two ends of the tie are moved simultaneously around a sheaf and crossed by the corresponding movement of both ends, corresponding catches of opposite series will be engaged by the expansion of the sheaf to interlock the ends of the tie at the point of 50 intersection.

55 In testimony that I claim the foregoing as my own I have hereto affixed my signature in the presence of two witnesses.

JAMES CONNELL PARKER.
